UNITED STATES PATENT OFFICE.

RUDOLPH OTTO, OF CHICAGO, ILLINOIS.

DESIGN FOR AN ASH-URN.

52,617.

Specification for Design.

Patented Oct. 29, 1918.

Application filed July 6, 1918. Serial No. 243,726. Term of patent 3½ years.

To all whom it may concern:

Be it known that I, RUDOLPH OTTO, a citizen of the United States, residing at Chicago, in the county of Cook and State of Illinois, have invented a new, original, and ornamental Design for Ash-Urns, of which the following is a specification, reference being had to the accompanying drawing, in which an elevation of the design is shown.

I claim:

The ornamental design for an ash urn, as shown.

In testimony whereof I affix my signature.

RUDOLPH OTTO.
